UNITED STATES PATENT OFFICE.

THOMAS J. BUSH, OF LEXINGTON, KENTUCKY.

INTERLOCKING BOLT.

SPECIFICATION forming part of Letters Patent No. 361,986, dated April 26, 1887.
Application filed July 21, 1884. Serial No. 132,421. (No model.)

To all whom it may concern:

Be it known that I, THOMAS J. BUSH, a citizen of the United States, residing at Lexington, in the county of Fayette and State of Kentucky, have invented certain new and useful 5 Improvements in Interlocking Bolts, of which the following is a specification, reference being had therein to the accompanying drawings.

The present invention is an improvement 10 upon the devices shown and claimed in Letters Patent Nos. 257,287, May 2, 1882, 264,622, September 19, 1882, and 301,668, July 8, 1884, here- 15 tofore granted to me; and it relates to certain improvements in interlocking bolts, portions thereof having been already referred to, but 20 not claimed, in Letters Patent issued to me September 19, 1882, numbered 264,622.

Figure 1 is a sectional elevation of a cross-tie and of a rail secured thereto by a pair of my 25 improved locking-bolts. Fig. 2 is a plan view of the bolts, showing the details of the interlocking portions. Fig. 3 illustrates a modified form, and is a sectional elevation similar to Fig. 1. Fig. 4 is a plan view showing the details 30 of the modification shown in Fig. 3.

Similar letters denote like parts.

The nature of the improvement consists in so forming the interlocking recess and the 35 lower portion of one member of each pair of bolts that they shall intersect in the same plane and be locked by imparting a quarter-turn to one of the pair, they being then tightened by means of screw-nuts at their outer ends, as here- 40 tofore described.

In the drawings, A represents the body of 35 one of the bolts, which is formed with a trans- 45 verse recess, a, located near its lower end, and preferably at right angles to the body A.

B is the second bolt, which, in addition to 40 a recess, b, similar in location to the one a, is cut away from the top of its recess to the end 45 of the bolt, as seen at d. This cut is made at right angles to the recess b and should include about half of the body of the bolt, leaving a square shoulder, c, at the bottom of the recess b, so that when the flattened lower portion of

the bolt B intersects the recess of the bolt A the recess b will allow said bolt to turn partly around on its own axis, thereby bringing the shoulder c squarely against the edge of the recess a.

As will be seen from the drawings, I contemplate using bolts curved at their upper ends, or made straight throughout, and in applying this form of my improved bolts the holes will be bored alike—that is to say, they will intersect in the common plane—and either bolt can be inserted in either hole.

A modified form adapted for use, as above described, is shown in Figs. 3 and 4, in which the bolt C is formed with an elongated aperture, D, instead of a recess, a.

The bolt E is faced off on both sides, as shown at e e, leaving the narrow wedge-like portion F, which passes readily through the aperture D, and is recessed on both edges at the desired point of intersection, where it is reduced to form the neck G.

In the present instance I have shown my improved bolts as applied to secure railway-rails 70 in position, the rails being represented at H and the cross-ties at J. When bolts with curved necks are used, an ordinary washer or fish-plate can be used; but where they are made straight a special form of washer will be re- 75 quired, as indicated at K, and more particu- 80 larly shown and described in another applica- 85 tion filed by me of even date herewith.

Having thus described my invention, what I claim as new is—

The bolt C, formed with a passage, D, in com- 80 bination with the bolt E, reduced to key with the bolt C, in combination with tie J, having intersecting diagonal holes, in which the bolts are inserted.

In testimony whereof I affix my signature in presence of two witnesses.

THOMAS J. BUSH.
